FOOT AND LAST MEASURING MACHINE

Harold M. Haskell, Nashua, N. H., and Seward M. Paterson, Brookline, Mass., assignors of one-half to J. F. McElwain Co., Boston, Mass., a corporation of Massachusetts, and one-half to Melville Shoe Corporation, New York, N. Y., a corporation of New York

Application February 26, 1930, Serial No. 431,423

9 Claims. (Cl. 33—3)

This invention relates to machines or apparatus for measuring feet, shoes, lasts, and the like.

It is the chief object of the invention to devise an apparatus of this character which will not only be useful in obtaining those measurements desired in fitting a shoe to a foot, but which will be more especially adapted for the collection of data upon which to base new designs of shoes, or information useful to shoe manufacturers or last makers for other reasons.

The nature of the invention will be readily understood from the following description when read in connection with the accompanying drawings, and the novel features will be particularly pointed out in the appended claims.

In the drawings,

Figure 1 is a perspective view of an apparatus constructed in accordance with this invention;

Fig. 2 is a plan view of the apparatus shown in Fig. 1;

Figs. 3 and 4 are elevations showing certain details of construction of the machine shown in Figs. 1 and 2; and

Fig. 5 is a side elevation, partly in section, showing the appliance for measuring the pitch of the curve at the back of the heel.

The machine shown in the drawings comprises a base 2 which may be made of any suitable material and which serves both as a support for the foot or last to be measured, and also to support the various units of the apparatus. It is preferable to support the foot in substantially the position that it takes when in a shoe; that is, with the heel elevated somewhat above the plantar or weight bearing surfaces of the forepart. For this reason the base is equipped with a heel support 3, Figs. 2 and 5, which has an upper, concaved, or cup-shaped surface to fit approximately the rounded plantar surface of the heel, the concave surface being located above the surface of the base at an elevation about equal to the height of a shoe heel. The foot should be supported in the machine with its longitudinal median axis substantially in the line or axis A—A, Fig. 2, the ball portion of the foot resting on the part 4 of the base. The position of the heel longitudinally in the axis A—A is determined by a stationary stop 5, Figs. 1, 2 and 5, usually made of metal and shaped to engage the rounded rear end of the heel.

Considering first the measurement of the length of the foot, it may be pointed out that the ordinary size of shoes, such as a "size 7" or "size 8" shoe, refers solely to length. Consequently, where the term "size" is used hereinafter it also will re-

fer simply to length unless qualified in some manner inconsistent with this use of the term.

In order to make the size measurement a length gage 6 is mounted for movement longitudinally of the axis A—A toward and from the toes of the foot, this gage consisting of a plate supported on a slide 7 which is mounted in a dove-tail guideway 8, as clearly shown in Figs. 1 and 3. A pointer 9 projects laterally from the gage 6 and cooperates with a scale 10 mounted on the base 10 to indicate the size of the foot being measured.

It is desirable both for the purpose of making the size determination, and also in making other measurements, to have the foot located in a substantially predetermined position on the base. 15

Its rearward position is determined by the stop 5, and in order to fix its position laterally an abutment 12 is provided to engage the side of the foot. Such an abutment may be made to contact with either side of the foot, but in the machine shown it has been arranged to engage the foot at the side of the great toe joint, or what sometimes is referred to as the "ball point" of the foot. 20

It is obvious that the position of this point will vary longitudinally with different sizes of feet, and that if feet of different sizes are located in the manner above described the position of the ball point also will vary laterally. The making of accurate measurements requires a standard position for this point in the respective 25

sizes of feet, and it is clear that in normal feet the location of this point will move outward and forward as the size or length increases, and that there should be a fixed relationship between the position of this point and the length of the foot. 30

Such a relationship is established and maintained in this apparatus between the size gage 6 and the lateral abutment 12. For this purpose the abutment is mounted on a slide 13 which is provided with a slot 14 to receive a pin 15 and the shank of a pin or screw 16. These parts 15 and 16 guide the slide 13 for movement in a definite path which is inclined forwardly and outwardly with reference to the axis A—A. The slide 13 also is provided with a rack 17, and the size gage 6 likewise has a rack 18 secured to it 35

by an arm 19. A gear 21 meshes with the rack 17 and also with a pinion 22 to which another gear 23 is fastened so that it rotates with the pinion, and the latter gear meshes with the rack 40

18. This gearing, therefore, transmits the adjusting movement of the size gage 6 to the abutment 12, and while the abutment moves in a different direction and at a slower rate than the size gage, it is compelled to move in a fixed path 45

18. This gearing, therefore, transmits the adjusting movement of the size gage 6 to the abutment 12, and while the abutment moves in a different direction and at a slower rate than the size gage, it is compelled to move in a fixed path 50

18. This gearing, therefore, transmits the adjusting movement of the size gage 6 to the abutment 12, and while the abutment moves in a different direction and at a slower rate than the size gage, it is compelled to move in a fixed path 55

and in a definite and fixed ratio to the movement of the size gage. This means that whenever the size gage is moved to a given size indication on the scale 10, the lateral abutment 12 will be moved to a definite and fixed position. Consequently, in measuring a foot, the heel portion of which has been properly placed against the stop 5, the gage 6 is advanced to meet the toe and the abutment 12 is simultaneously moved into engagement with the side of the foot at the great toe joint. If the position of the foot is such that the abutment strikes the side of the foot before the gage 6 meets the toe, then the foot should be shifted outward slightly. On the other hand, if the gage 6 strikes the toe while the abutment 12 is still out of contact with the foot, then the foot should be moved inwardly until the ball point strikes the abutment.

The foot then is in a definite position such that the other measurements desired can be made with the certainty that variations in them are not due to variations in the position of the feet.

The foot now having been positioned definitely the width measurement can be made, and for this purpose a width gage 25 is arranged to be moved into contact with the side of the foot opposite the abutment 12. This gage consists of a plate mounted on a slide 26 supported in a dove-tail guideway 27. A coiled spring 28 mounted in a groove in the lower side of the base acts on the slide 26 to press the gage 25 against the foot in the region at or adjacent to the little toe joint, the spring being used for the purpose of applying substantially the same pressure in all cases. Secured to the slide 26 is a scale 30 which cooperates with a stationary scale 31 to give width measurements. The scale 30 bears size designations and the scale 31 width indications, so that when the size or length of the foot has been determined the clerk or attendant then finds the correct width on the scale 31 opposite to the size designation on the scale 30.

Since the width measurement as read on the scale 31 will depend not only on variations in the width of feet but also on the position in which feet of different sizes are located by the abutment 12, we have found it preferable to make the angle of adjustment of this abutment such that the lateral component of its movement, in moving from one size adjustment to the next, is somewhat less than, and preferably one-half of, the normal difference in width between said sizes. This means that normal feet of medium width, say width C, will be approximately centered in the apparatus.

There is considerable difference in the width of the heel portions of feet which becomes an important factor both in the manufacture of shoes and in the fitting of them. In order to measure such difference a pair of caliper jaws 32 and 33 are mounted to engage the opposite sides of a heel positioned against the stop 5. Preferably these jaws are both pivoted on a common pivot stud or screw 34 located behind the stop 5 and substantially in the axis A—A. A spring 35 connects them and tends to press them against the opposite sides of the heel being measured. The jaw 33 has a plate-like extension or arm 36 projecting beyond its pivot and provided with a scale 37, while the other jaw carries a pointer 38 mounted to cooperate with said scale 37 to indicate variations in the widths of heels. Step lugs 40, Fig. 2, on the two jaws cooperate to limit their range of movement toward each other.

In order to center these parts when there is no foot in the apparatus, a spring 41 is coiled around a rod 42 which is pivoted at 43 to a projection from the jaw 33, the spring bearing at one end against said projection and at its opposite end against a stationary lug 44 through which the rod 42 extends. This spring, therefore, tends to hold the arm 36 of the jaw 33 in contact with the stop 45.

At the back of the ankle and immediately above the heel, or at approximately the junction of the rear surfaces of the heel and ankle, there is an inward curve which requires particular attention in the manufacture of low shoes. The degree of this curvature, or, in other words, the longitudinal relationship of this surface to the extreme rear end of the heel, varies materially in different feet. In order to measure these variations the machine shown is equipped with a device 46, best shown in Fig. 5, as consisting of an arm mounted on a horizontal pivot 47 and adapted to swing through a slot formed centrally in the heel stop 5, as illustrated in Fig. 2. In Fig. 5 this arm 46 is shown swung somewhat to the rear of its normal position. A spring 48 acts on an extension 49 of the arm 46 to urge this arm forward. When the heel of a foot to be measured is placed against the stop 5, the upper end portion of the arm 46 engages the curve at approximately the junction of the rear surface of the ankle with the heel and pushes the arm backward against the action of the spring 48 to a degree depending upon the contour of this portion of the foot. The extent to which this arm is forced backwardly is measured by a pointer 50, Fig. 5, rigid with the arm 46 and mounted to swing along a scale 51 on the stationary bracket 52.

The height or thickness of the foot at the instep and immediately over the ball point are important factors in making shoes that will fit comfortably and will set smoothly. For the purpose of measuring these elevations an arm 53 is arranged to be moved into engagement with either the instep or the part of the foot directly over the ball, as desired. This arm is supported for adjustment on two rods or posts 54, both fixed in one end of the dove-tail slide 55 which is supported for adjustment horizontally in a metal plate 56 grooved to receive the slide. Said plate is secured to the base 2 and supports the slide for movement longitudinally of the base and parallel to the axis A—A. A yoke 57 connects the upper ends of the posts 54 and holds them in alignment, and the fit of the arm 53 on these posts is such that it will be held by friction to any position to which it is moved. One of the posts 54 is graduated in inches and fractions thereof, or in any other desired manner, so that the height of the arm can be read on the scale 58.

It is desirable that the measurements of the thickness or height of the instep and ball portion of the foot shall be taken at the same points on all feet of the same size and the plate 56 therefore is provided with a size scale 59 to cooperate with a line 60 on the slide 55 in setting the arm 53 properly for making the instep measurements. A size scale 61 on the plate 56 cooperates with a mark 62 on the slide to determine the longitudinal position of the slide, and hence the arm 53, in measuring the height of the foot at the ball. The slide 55 may be secured in any adjusted position by a clamp 70 set into the plate and having a thumb screw threaded through it and into the metal plate 56.

It is desirable to measure the height of the arch since this dimension varies substantially in differ-

ent feet, and for this purpose a device 64 is mounted to be brought into engagement with this part of the foot. The part 64 forms one member of an arch measuring attachment which is arranged to be mounted on, or removed from, the machine as a unit. This unit comprises a bracket 65 provided with a split clamp portion through which a hole 66, Fig. 2, is formed to receive an upright post 67 that projects rigidly from a plate 68 secured on the base 2. A thumb screw 69 is threaded through the split clamp portion of the bracket to bind this member securely on the post 67.

The arch engaging member 64 is supported on the lower ends of two rods 71 and 72, respectively, Fig. 1, both guided in an extension 73 of the bracket 65. A third rod 74 secured in the part 73 cooperates with the rod 72 to guide a cross head 75, this cross head being secured fast to the rod 72 but sliding on the rod 74. A spring 76 encircles the former rod and abuts at its opposite ends against the members 73 and 75, thus tending to elevate the cross head and serving, therefore, to raise the device 64 into engagement with, and to press it against, the arch of the foot being measured.

The point at which the movement of this device is arrested by its contact with the arch of the foot is indicated on a scale 78 formed on the outer edge of a curved part 79 of the bracket 65, a pointer 80 being provided to swing over this scale. This pointer is carried by a toothed sector 81, Fig. 1, mounted to swing on the pivot screw 82 and meshing with a rack 83 which is secured to the cross head 75. The arrangement is such that this indicating mechanism multiplies and amplifies or increases the movement of the arch engaging device 64 and therefore permits the measurement of variations in the elevation of arches of different feet with a high degree of accuracy.

The arch engaging device 64, when in its elevated position, offers some obstruction to the initial positioning of the foot and it may, therefore, be depressed into the cavity or recess 84 formed in the base plate and locked in its depressed position by a thumb screw 85 which is threaded through the bracket member 73, the inner end of the screw being arranged to engage the rod 71.

Since it is desirable to measure the height of the arch at its point of maximum elevation, and since this point will vary in feet of different sizes, the bracket 65 is mounted to swing on the post 67 so as to adjust the device 64 longitudinally of the arch. The base plate 68 is provided with a scale 86, Fig. 2, graduated in sizes and arranged to cooperate with the side of the bracket 65 so that the bracket can be adjusted to the proper position for measuring the elevation of the arch of any individual size of foot. This ensures the measurement of arches of feet of the same size at substantially the same point lengthwise of the foot.

It will now be appreciated that the invention provides a relatively compact machine which is particularly adapted for the collection of information or data useful to the shoe manufacturer and the last maker. Such information not only is valuable in the designing of shoes and lasts, but is useful also in connection with certain shoe making operations, in the checking of the measurements of lasts, and for a variety of other purposes. The particular machine shown is designed more especially for the measurement of men's feet. It will be evident, however, that the same

machine can readily be calibrated for measuring and classifying the lasts for men's feet, and that machines of the same organization, but differing somewhat in dimensions, can be made for measuring women's and children's feet in any desired range, and the lasts used in these ranges. In the appended claims, therefore, a last is regarded as the equivalent of a foot.

While we have herein shown and described a preferred embodiment of the invention, it will be understood that the invention may be embodied in other forms without departing from the spirit or scope thereof.

Having thus described our invention, what we desire to claim as new is:

1. A foot measuring apparatus comprising, in combination, a base for supporting a foot, a stop for engaging the rear end of the heel and determining its position on said base, a slidable abutment for engaging the side of the foot, a size gage adjustable toward and from the toe of the foot, and positive connections between said abutment and said gage for causing the abutment to move longitudinally and laterally of the foot simultaneously with the adjustment of said gage but at a different rate and in a definite fixed ratio to the movement of the gage.

2. A foot measuring apparatus comprising, in combination, a base for supporting the foot in measuring position, a stop on said base against which to position the rear end of the heel, an adjustable abutment for engaging the side of the foot, a size gage adjustable toward and from the toe of the foot, gear connections between said abutment and said gage for transmitting the adjustment of one to the other in a definite fixed ratio, and means for guiding said gage and said abutment to cause the abutment to be moved both longitudinally and laterally of the foot by said adjustment.

3. A foot measuring apparatus comprising, in combination, a base for supporting the foot in measuring position, a stop on said base against which to position the rear end of the heel, an abutment for engaging the side of the foot, means supporting said abutment for adjustment laterally to center feet of different sizes on said base, a size gage adjustable toward and from the toe of the foot, two slides on which said gage and abutment, respectively, are mounted, means for guiding said slides for movement in different directions, racks on said slides, and gearing meshing with said racks and serving to transmit the adjustment of one slide to the other in a definite and fixed ratio.

4. A foot measuring apparatus comprising, in combination, a base for supporting the foot in measuring position, a stop on said base against which to position the rear end of the heel, an abutment for engaging the side of the foot, means for supporting said abutment for movement in a fixed path inclined forwardly and laterally away from the position normally occupied by the longitudinal median axis of the foot, a rack movable with said gage, a second rack movable with said abutment, and gearing meshing with said racks and serving to transmit the adjustment of said gage to said abutment in a definite and fixed ratio.

5. A foot measuring apparatus comprising, in combination, a base for supporting a foot with its longitudinal median axis in approximately a predetermined position, a stop for engaging the rear end of the heel and determining its position on said base, a slidable abutment for engaging the

- side of the foot, at the great toe joint, means supporting said abutment for movement in a fixed path inclined forwardly and laterally away from said axis at an angle such that the adjustment of said abutment from one size to another moves the abutment laterally about half the normal difference in width between said sizes, and a width gage adjustable to engage the side of the foot in the region of the little toe joint.
6. A foot measuring apparatus comprising, in combination, a base for supporting the foot in measuring position, a stop on said base against which to position the rear end of the heel, an abutment for engaging the side of the foot at the great toe joint, means supporting said abutment for lateral adjustment, a size gage adjustable toward and from the toe of the foot, positive connections between said abutment and gage for adjusting the abutment laterally a predetermined distance for each unit of length adjustment of said gage, a width gage adjustable to engage the side of the foot in the region of the little toe joint, a spring for pressing said width gage laterally against the foot, and a scale cooperating with the latter gage to give width designations.
7. A foot measuring apparatus comprising, in combination, a base for supporting a foot in measuring position, a stop on said base against which to position the rear end of the heel, a pivoted member for engaging the rear curved surface of

the ankle at approximately its junction with the heel, a spring for pressing said device against said curved surface, and a scale cooperating with said device to indicate variations in the relationship of said surface to the rear end of the heel.

8. A foot measuring apparatus comprising, in combination, a base for supporting a foot in measuring position, a stop on said base against which to position the rear end of the heel, a device for engaging the arch of a foot supported in measuring position, means supporting said device for up and down movement, an indicator for measuring the movements of said device comprising a rack connected with said device to move with it, a sector meshing with said rack, an arm carried by said sector, and a scale over which said arm moves.

9. A foot measuring apparatus comprising, in combination, a base for supporting a foot in measuring position, a stop on said base against which to position the rear end of the heel, a device for engaging the rear curved surface at approximately the junction of the back of the ankle with the heel, means for operatively supporting said device, and a scale cooperating with said device to indicate variations in the relationship of said surface to the back of the heel in a direction longitudinally of the foot.

HAROLD M. HASKELL.

SEWARD M. PATERSON. 30
